UNITED STATES PATENT OFFICE

105,238

DESIGN FOR A FLEXIBLE POCKET RECEPTACLE

Warner R. Buxton, Longmeadow, Mass.

Application March 29, 1937, Serial No. 68,451

Term of patent 14 years

To all whom it may concern:

Be it known that I, Warner R. Buxton, a citizen of the United States, residing at Longmeadow, in the county of Hampden and State of Massachusetts, have invented a new, original, and ornamental Design for Flexible Pocket Receptacles, of which the following is a specification, reference being had to the accompanying drawing, forming part thereof.

Fig. 1 is a top edge view; and

Fig. 2 is a face view showing the front face of a flexible pocket receptacle embodying my new design.

Fig. 3 is a perspective sectional view to show

the stepped relation of the pocket edge, taken substantially on line 3—3 of Fig. 2.

The design appears wholly on the front face of the flexible pocket receptacle as shown in Fig. 2.

The dominant feature of the design is the elongated diamond configuration formed by the stepped edge outlines of adjacent superposed pockets.

I claim:

The ornamental design for a flexible pocket receptacle substantially as shown and described.

WARNER R. BUXTON.
